UNITED STATES PATENT OFFICE.

JOHN BIGELOW, OF NEW YORK, N. Y.

DESIGN FOR AN APPAREL-BELT.

SPECIFICATION forming part of Design No. 20,640, dated March 31, 1891.

Application filed January 17, 1891. Serial No. 378,153. Term of patent 7 years.

To all whom it may concern:

Be it known that I, JOHN BIGELOW, a citizen of the United States, residing at New York, in the county of New York and State 5 of New York, have invented and produced a new and original Design for a Belt; and I do declare the following to be a full, clear, and exact description of the same, reference being had to the accompanying drawings, forming a part thereof.

Figure 1 is a perspective view of a belt, showing my design. Fig. 2 is a front elevation of the belt as in use.

The leading feature of my design for what 15 I call a "vestlette" is an apparel-belt, the outlines of which, as shown in the drawings, have the conventional shape and appearance of an abbreviated vest.

A and B are the two portions of the front, 20 having between them the vertical line a. The

upper and lower lines a' and b of these front portions are nearly parallel, slightly flaring at the lower front end; but at their respective rear ends they slope away and finally terminate in narrow extensions C D. On each 25 front part the usual place of the pocket of a vest is marked by a parallelogram E. In the place where buttons on a vest are used are small circles F, and at the right of each is a black line to indicate the button-hole in a vest. 30

What I claim is—

The design for an apparel-belt herein shown and described.

In testimony whereof I affix my signature in presence of two witnesses.

JOHN BIGELOW.
